LOADING-MACHINE.

1,851,953.

Specification of Letters Patent.

Patented Sept. 7, 1920.

Application filed October 17, 1916. Serial No. 126,184.

To all whom it may concern:

Be it known that I, Nils D. LEVIN, a citizen of the United States, residing at Columbus, in the county of Franklin and State of Ohio, have invented certain new and useful Improvements in Loading-Machines, of which the following is a specification, reference being had therein to the accompanying drawing.

10 The present invention relates to certain new and useful improvements in loading machines and especially to that class of loading machines which is adapted to use in mines or tunnels for the transfer of broken material from the working face to conveniently placed cars for transportation from the mines. In the mining of coal, it is the common practice to break down the material by blasting in the face of the vein. 15 The material thus broken down lies in heaps adjacent the working face from which it is loaded into cars or similar receptacles for transportation from the mine. Owing to the limited space the labor of loading usually is extremely arduous, and when the working face has a considerable width, often as much as 25 or 30 feet, the material from the sides of the room or tunnel must be handled two or three times in the process 20 of loading. The extremely limited vertical dimensions of the working places, and the necessity for placing roof supporting timbers relatively close to the working faces, present difficulties to the adaptation of mechanical loaders to use in coal mines. One 25 of the greatest of these difficulties is to so support the conveyer element of the machine that coal may at all times be delivered to, and distributed along, a pit car placed 30 upon the mine track in the rear of the machine, while the receiving end of the conveyer may be made available to receive coal 35 at any part of the working face.

It is the special object of the present invention to provide improved conveying mechanism and mountings therefor, adapted to convenient manipulation about the working place, to facilitate the transfer of broken material from the working face to 40 cars or similar receptacles for transport from the mine. One form of this invention is set forth in the following specification, reference being had to the accompanying

drawings, but it is to be understood that variation may be made in the details of the construction without departing from the spirit of the invention.

Of the drawings—

Figure 1 is a side elevation of the preferred embodiment of my invention. 60

Fig. 2 is a plan view of the machine illustrated in Fig. 1.

Fig. 3 is a section along the line 3—3 of Fig. 2.

Fig. 4 is a section along the line 4—4 of Fig. 2. 65

Fig. 5 is a fragmentary section along the line 5—5 of Fig. 1.

Fig. 6 is a detailed plan view of the power devices by which the conveyer is actuated. 70

Figs. 7 to 13 inclusive are diagrammatic showings of the operation of the machine.

Like numerals refer to similar parts in the several figures.

This machine comprises, primarily, a conveyer member of the well known chain and scraper type, having a horizontal receiving part adapted to rest upon the floor of the mine adjacent the working face, an upwardly and rearwardly inclined central part 75 and a horizontal part adapted to extend above the conveniently placed car to deliver the material thereto, and supporting members adapted to facilitate positioning the said conveyer member for use, and for moving it from place to place. This conveyer consists of an elongated trough composed of side plates 1 and the bottom plate 2 along which travels two endless chains 3 which are joined together at spaced intervals by the scraper cross bar 4. Attached to the side plates 1 are angle bars 5 the flanges of which extend above the chains 3 to shield them from contact with the material traveling along the trough. Other longitudinal 80 angle bars 6 are fixed to the side plates 1 and to these is attached the bottom plate 7 which serves as a slide way for the return strand of the conveyer chains and scrapers. At the rear end of the conveyer are 85 castings 8 having slideways 9 in which are slidable the journal bearings 10 of the head shaft 11. To the head shaft 11, are fixed the rollers 12 around which pass the chains 3. Adjusting screws 13 are provided to 90 move the bearings 10 in the slideways 9 to

adjust the tension of the chains 3 in a manner common in conveyer practice. At the lower or receiving end of the conveyer the chains 3 pass around a stationary cross bar 5 14 to which is attached two guide bars 15 adapted to engage the rollers 16 of the chains 3 to guide them from the lower to the upper run of the conveyer. Attached to the side plates 1 of the inclined and upper 10 horizontal parts of the conveyer trough, by means of strap bars 17, are flaring side plates 18 which serve to prevent the overflow of material from the conveyer trough. The lower horizontal part of the conveyer trough is provided with removable plates 19 having stiffening bars 20 the projecting ends of which are adapted to be inserted in sockets 21 attached to the side plates 1. At the forward end of the conveyer 15 the bottom plate 7 extends on either side of the conveyer trough and is bent upward to form a skid shoe 22 adapted to slide readily over the floor of the mine. Near the forward end of the conveyer is provided a cross bar 23 projecting at either side to form 20 handles 24 convenient for lifting and moving the forward end of the conveyer. Attached to the conveyer trough, equidistant from its ends, is a structural framework 25 having horizontal members 26 which are 25 adapted to serve as a supporting base for the conveyer, as will be hereinafter set forth. Mounted in this structural framework 25 is an electric motor 27 by which power is supplied to actuate the conveyer. The armature pinion 28 of the motor 27 engages 30 a spur gear 29 which is mounted upon the cross shaft 30 and is adapted to be connected thereto by a friction clutch 31, of 35 the well known multiple disk type, having a controlling hand wheel 32 by which the friction elements of the clutch may be readily engaged or disengaged. Attached to the opposite end of the shaft 30 is a spur 40 pinion 33 which engages a spur gear 34 fixed to a second cross shaft 35. The shafts 30 and 35 are journaled in bearings 36 and 37 formed in the extending arms 38 of the motor frame casting. Attached to the shaft 45 35, between the bearings 37, is a sprocket wheel 39 which is connected through the chain 40 with a similar sprocket wheel 41 attached to the driving shaft 42. The driving shaft 42 is journaled in bearings 43 attached to the structural steel framework and is provided with two sprocket wheels 44 the 50 rims of which extend through convenient slots 45 in the bottom plate 7 and engage the chains 3 to drive them. The bottom 55 plate 7 is curved downwardly at 46 to form loops in the chains 3 affording a sufficient contact, with the sprocket wheels 44 to satisfactorily drive the chains. 47 is a conductor cable, extending from a source of electric 60 supply through which current is supplied to

actuate the motor 27. A suitable switch 48 is provided to control the operation of the motor.

The conveyer member as above described, constitutes a self contained structure which, 70 when used in conjunction with the auxiliary parts to be hereinafter described, may be easily handled by the miner and his helper and moved about the mine and so positioned that its receiving portion will be convenient 75 to material at any part of the working face, and its delivery end above the car which is to be loaded. As a supporting base for the above constituted conveyer member I have provided a skid rail 55 adapted to be horizontally supported transversely of the mine room, and to lateral movement toward and from the pile of material which is to be loaded. The horizontal members 26 of the conveyer structure bear upon this skid rail. 80 55, the weight being so distributed that the receiving end of the conveyer will rest lightly upon the ground. The skid rail is formed of a suitable channel bar the flanges of which are turned upward to engage the lug 25^a attached to the underside of the framework 25 to prevent longitudinal movement of the conveyer transversely of the skid rail. The web of the skid rail 55 is perforated at spaced intervals with apertures 56 into 90 which the end of a pinch bar may be inserted to pry the conveyer frame along the skid rail to the desired position. One end of the skid rail is supported during the operation of the machine upon a truck having 100 a platform 50 supported upon axles 51 and wheels 52 adapted to travel along the rails of the mine track.

The end of the skid 55 remote from the truck 50 is supported upon a horizontal rail 105 57 built up of two steel bars 58 secured together in spaced parallelism by suitable space blocks 59 and rivets 60. Extending between the bars 58 near each end of the rail 57 are jack posts 61, of the type commonly 110 used in mines, the lower ends of which rest on the floor of the mine, and have screw threaded extensions 62 adapted to be forced against the mine roof by the hand wheel nuts 63 to hold the jacks securely in place. 115 Near each end of the supporting rail 57 is an aperture adapted to register with any of a plurality of apertures 64 spaced longitudinally of the jack post 61 through which the pins 65 may be thrust to support the 120 rail 57 at the desired elevation above the floor of the mine.

When being transported from one part of the mine to another, the conveyer rests upon the truck platform 50 its length parallel 125 with the track, as shown in Fig. 8, the rear end of the horizontal member 26 bearing upon the platform 50. A convenient block 54, placed upon the platform 50 beneath the forward ends of the members 26, elevates 130.

the receiving end of the conveyer clear of the track to permit travel therealong, as illustrated in Fig. 7. Upon arrival at the working place the forward end of the conveyer is lifted by the helper, as shown in Fig. 9, to allow the miner to remove the block 54 and to insert the skid rail 55 beneath the member 26. The supporting rail 57 is then attached to the jack posts 61 at the desired position above the floor of the mine and the posts are tipped as shown in Fig. 10, to allow the placing of the rail 57 under the end of the rail 55, after which the jack posts 61 are straightened up and the hand wheels 63 adjusted to force the upper post sections 62 against the roof, as shown in Fig. 11. The conveyer is then slid along the skid rail 55 to such position that the receiving end may be placed near to the material which is to be loaded, and the delivery end above the car 66 upon the track in the rear of the machine. The removable side plate 19 is then placed at whichever side of the conveyer is convenient to the operator, the motor is started to drive the conveyer, and material shoveled upon the forward receiving section to be carried upward and rearward and discharged into the car. When the material within convenient reach of the operator has been loaded the conveyer will be moved along the skid 55 to bring its receiving section within shoveling distance of other material and the operation continued as before. Should it be desirable to move the conveyer forward into more convenient reach of the material, the skid rail 55 may be moved longitudinally of the supporting rail 57 and the truck 50 advanced along the rails 53 until the desired position is reached as illustrated in Fig. 12 and Fig. 13. As soon as the car is loaded the motor is stopped, the car removed and an empty one set in its place. During the interval of changing cars material may be shoveled onto the receiving section of the conveyer and moved rearwardly, by successively starting and stopping the motor, until the trough is full. The conveyer thus becomes a reservoir having a capacity sufficient, under normal conditions, to keep the shovelers continuously busy. This material will be immediately delivered to the car when it is ready for loading and the conveyer allowed to run until the car is fully loaded.

When the machine is to be moved to another working place, the conveyer is moved longitudinally of the skid rail 55 to the center of the truck platform 50 and turned longitudinally of the mine track. The helper then seizes the handles 24 of the cross bar 23, lifts the forward end of the conveyer, allowing the frame 25 to heel upon the platform 50, as shown in Fig. 9. The skid rail 55 is then withdrawn, the block 54 replaced and the machine lowered into position for traveling as shown in Fig. 7. The skid rail 55, the supporting rail 57, the jack posts 61, and other paraphernalia are loaded upon the truck, or the conveyer trough, and the machine is ready for travel.

The present mechanism has all of the advantages incident to the loading mechanisms heretofore made, each of which has an elevating conveyer that is mounted on a vertical axis which is relatively fixed in relation to its supporting truck. All of the earlier mechanisms within this class of conveyers have been characterized by the presence of such a relatively fixed vertical pivot. And, because of its presence the receiving part of the conveyer was held to an arc line which was fixed in relation to the truck, and hence the conveyer had to be very long in order to reach to points laterally remote from the truck, and the truck had to be repeatedly bodily moved forward and backward.

With a mechanism like the present one there are a large number and a wide variety of curved paths through which the front end of the elevating and conveying element can be shifted both laterally and forward and back without moving the truck support. The lug 25^a and the guide 55 with its flanges, serve as a pivotal or hinging mechanism for the conveyer frame. This hinge mechanism is such that its axis can be shifted laterally without requiring any movements of the truck. A slight movement of the pivot device is multiplied into a long movement at the receiving end of the elevator, and this is done without materially shifting the rear end of the conveyer in relation to the receiving car. And, again, the pivot device can be moved forward or backward either by moving the outer end of the guide skid 55, or by sliding the inner end of the guide forward or backward of the car or by adjusting both ends of the guide skid as desired. And, as with earlier devices there can be longitudinal adjustment by moving the truck bodily forward or back. But, as will be seen, the truck, at times, when the elevator is in operation is serving merely as a support which is companion to the outer support 58, and other supports for the inner end of the guide can, if desired, be substituted.

The pivot, or point of vertical support for the elevator frame, can be positioned at a place very remote from the truck and this can be done upon either the right side or the left side of the latter.

I, for brevity, herein refer to the working element of the mechanism as a "self contained conveyer", meaning thereby that this element comprises its own independent frame, an endless conveyer of suitable form, mounted on the frame, a trough or holder

correlated with the conveyer and also on the frame, a motor and motor support forming part of or rigidly connected to the conveyer frame, and power transmitting devices supported on the frame and interposed between the motor and conveyer, all these making a unitary structure which is readily separable from the other elements. This element, the self contained conveyer, can be picked up and transported from place to place, disconnected from the means which support it from the ground, without in any way throwing any of its working parts out of relation with the others. For sustaining it when at work, I provide a two-part support, one part being a primary support which rests upon the ground, and the other being a secondary support between the primary support and the conveyer. The primary support is, in the construction shown, composed of two parts, one being a truck or car at one end of the apparatus, and the other being posts or rails at the other end. The secondary or intermediate support is, in relation to the points of delivery of the material and to the points where the load is received, movable universally, being without rigid engagement with the primary support, that is, it can slip bodily transversely at any time, or can slip bodily forward or backward at either end or both ends. The primary support, similarly, can, at either of its ends or at both ends, be moved backward or forward relatively to the secondary support. And the conveyer itself can be moved transversely independently of the secondary support and, together with it, can be moved in either direction, transversely, or forward or backward, in relation to the primary support.

My mechanism is therefore readily distinguishable from those in which the conveyer element has been in some way positively governed in its movements by the truck mechanism, or by a frame connected therewith.

What I claim is:

1. In a machine of the class described, the combination with a self contained conveyer comprising an elongated frame and conveyer and power devices mounted within said frame, of a removable substantially horizontal rail extending transversely beneath said frame upon which said conveyer may be moved to and supported in operative position, a collapsible support for said rail, and means to prevent the collapse of said support.

2. In a machine of the class described, the combination with a self contained conveyer comprising an elongated frame and conveyer and power devices mounted within said frame, of a removable substantially horizontal rail extending transversely beneath said frame upon which said conveyer may be

moved to and supported in operative position, a collapsible support upon which said rail may slide laterally toward and from the material to be loaded, and means to prevent the collapse of said support. 70

3. In a machine of the class described, the combination with a self contained conveyer comprising an elongated frame and conveyer and power devices mounted within said frame, of a removable transversely extending substantially horizontal rail upon which said frame is slidably supported and is adapted to horizontal rotary movement relative thereto and bodily movement longitudinally thereof. 75

4. In a machine of the class described, the combination with a self contained conveyer comprising an elongated frame and conveyer and power devices mounted within said frame, of a removable substantially horizontal rail extending transversely beneath said frame upon which said conveyer is supported and is adapted to horizontal rotary movement relative thereto and bodily movement longitudinally thereof, a collapsible support upon which said rail is removably and slidably supported, and means to prevent the collapse of said support. 80

5. In a machine of the class described, the combination with a self contained conveyer comprising an elongated frame and conveyer and power devices mounted within said frame, of a removable substantially horizontal rail extending transversely beneath said frame upon which said conveyer rests 95 and is adapted to horizontal rotary movement relative thereto and bodily movement longitudinally thereof, a collapsible support upon which said rail may slide laterally toward and from the material to be loaded, 100 and means to prevent the collapse of said support. 105

6. In a machine of the class described, the combination with a self contained conveyer comprising an elongated frame and conveyer and power devices mounted within said frame, of a removable transversely extending substantially horizontal rail upon which said frame is slidably supported and is adapted to horizontal rotary movement relative thereto and bodily movement longitudinally thereof, and means to prevent longitudinal movement of said conveyer relative to said frame. 110

7. In a machine of the class described, the combination of a supporting rail, a conveyer supported on the rail, a support for the rail in fixed relation to one end thereof and movable along the track of the mine, and a second support for the rail in movable relation 115 with its other end and in fixed relation to the coal face. 120

8. In a machine of the class described, the combination of a supporting rail, a conveyer supported on the rail, a wheeled support for 125

one end of the rail adapted to travel along the mine track, and a fixed elongated support for the other end of the rail along which said rail may be moved relative to the material to be loaded.

9. In a machine of the class described, the combination of a supporting rail, a self-contained conveyer removably supported on the rail and adapted to horizontal rotary movement relative thereto and lateral movement longitudinally thereof, means to prevent longitudinal movement of the conveyer relative to the rail, a wheeled support for one end of the rail adapted to travel along the mine track, and a fixed support for the other end of the rail along which said rail may be moved relative to the material to be loaded.

10. In a machine of the class described, the combination with a structure comprising an inclined elongated conveyer frame rigidly attached to a centrally disposed supporting frame which includes the center of gravity of the structure and which has a flat bottom member upon which said structure rests, of a conveyer mounted within said conveyer frame, power devices within said supporting frame arranged to actuate said conveyer and a removable substantially horizontal rail extending transversely beneath said bottom member upon which said structure may be moved to and supported in operative relation with the material to be loaded.

11. In a machine of the class described, the combination with a structure comprising an inclined elongated conveyer frame rigidly attached to and projecting at both ends beyond a centrally disposed supporting frame which includes the center of gravity of the structure and which has a flat bottom member upon which said structure rests, of a conveyer mounted within said conveyer frame, power devices within said supporting frame arranged to actuate said conveyer, and a removable substantially horizontal rail extending transversely beneath said bottom member upon which said structure may be moved to and supported in operative relation with the material to be loaded.

12. In a machine of the class described, the combination with a self contained conveyer comprising an elongated frame and conveyer and power devices mounted within said frame, of a removable substantially horizontal rail extending transversely beneath said frame upon which said conveyer may be moved to and supported in operative position, and supports upon which said rail is movable.

13. In a machine of the class described, the combination with a self contained conveyer comprising an elongated frame and conveyer and power devices mounted within said frame, of a removable substantially horizontal rail extending transversely beneath said frame upon which said conveyer

may be moved to and supported in operative position, a support upon which said rail is movable, and means for holding said support in fixed relation to the material to be loaded.

14. In a machine of the class described, the combination with a self contained conveyer comprising an elongated frame and conveyer and power devices mounted within said frame, of a removable transversely extending substantially horizontal rail upon which said frame may slide to and be supported in operative position, and supports for said rail.

15. In a machine of the class described, the combination with a self contained conveyer comprising an elongated frame and conveyer and power devices mounted within said frame, of a removable substantially horizontal rail extending transversely beneath said frame upon which said conveyer may be moved to and supported in operative position, a wheeled support for one end of said rail, and a fixed support upon which the other end of said rail is movable.

16. In a machine of the class described, the combination of a supporting rail, a self-contained conveyer removably supported upon the rail, a wheeled support for one end of the rail and a fixed elongated support for the other end of the rail along which said rail may be moved relative to the material to be loaded.

17. In a machine of the class described, the combination with a structure comprising an inclined elongated conveyer frame rigidly attached to and projecting at both ends beyond a centrally disposed supporting frame which includes the center of gravity of the structure and which has a flat bottom member upon which said structure may rest and slide either laterally or rotatively in horizontal planes, of a conveyer mounted within said conveyer frame, and power devices within said supporting frame arranged to actuate said conveyer.

18. In an apparatus of the class described, the combination with a truck, of a guide projecting laterally from said truck and movable forward and backward thereon, and a self contained conveyer comprising an elongated frame and conveyer and power devices mounted within said frame, said frame resting exclusively and bodily slidably laterally upon said guide to vertical lines outside the vertical lines of the truck.

19. In an apparatus of the class described, the combination with a truck, of a guide projecting laterally from said truck and movable forward and backward thereon, a self contained conveyer comprising an elongated frame and conveyer and power devices mounted within said frame, said frame resting upon said guide and adapted to horizontal rotary movement relative thereto and bodily

- sliding movement longitudinally thereof to vertical lines outside the vertical lines of the truck.
20. In an apparatus of the class described, the combination with a truck, of a guide supported on and bodily movable transversely of said truck, and a self contained conveyor comprising an elongated frame and conveyor and power devices mounted within said frame, said frame resting upon said guide and adapted to horizontal sliding movement relative thereto.
21. In an apparatus of the class described, the combination with a truck, of a guide supported on and bodily movable transversely of said truck, and a self contained conveyor comprising an elongated frame and conveyor and power devices mounted within said frame, said frame resting upon said guide and adapted to horizontal rotary movement relative thereto and bodily sliding movement longitudinally thereof.
22. In an apparatus of the class described, the combination of the truck, the support supplemental to the truck and adapted to be made stationary independently of the truck, the guide engaging with the said support and with the truck, and the laterally swinging conveyor bodily movable along said guide.
23. In an apparatus of the class described, the combination of the approximately horizontally disposed guide, the laterally swinging conveyor mounted on and bodily movable along the guide, a supporting device for the guide at one end thereof, and a vertically adjustable supporting device at the other end, substantially as set forth.
24. In an apparatus of the class described, the combination of the substantially horizontally positioned guide, the laterally swinging conveyor mounted on and bodily movable along the guide, a support for one end of the guide, a relatively elongated support for the other end of the guide, means for adjusting the said support bodily vertically, and means for adjusting one of its ends independently of the other.
25. An apparatus for loading coal in mines comprising a horizontally extending rail supported in substantial parallelism with the coal face and adjustable relative thereto, and an elongated self contained conveyor resting upon said rail and movable thereon and therewith to permit the positioning of the receiving end of said conveyor in convenient proximity to material adjacent to any part of said coal face while maintaining its delivery end in loading relation above a pit car suitably positioned upon the mine track.
26. An apparatus for loading coal in mines comprising a horizontally extending rail supported in substantial parallelism with the coal face and adjustable relative thereto, and a transversely extending self contained elongated conveyor resting upon said rail and adapted to be laterally moved longitudinally thereof and to be horizontally rotated thereon to permit the positioning of the receiving end of said conveyor in convenient proximity to material adjacent to any part of said coal face while maintaining its delivery end in loading relation above a pit car suitably positioned upon the mine track.
27. An apparatus for loading coal in mines comprising a horizontally extending rail supported in adjustable relation to a coal face, and an elongated self contained conveyor resting upon said rail and movable thereon and therewith to permit the positioning of the receiving end of said conveyor in convenient proximity to material adjacent to any part of said coal face while maintaining its delivery end in loading relation above a pit car suitably positioned upon the mine track.
28. An apparatus for loading coal in mines comprising a horizontally extending rail supported in adjustable relation to a coal face, and a transversely extending self contained elongated conveyor resting upon said rail and adapted to be laterally moved longitudinally thereof and to be horizontally rotated thereon to permit the positioning of the receiving end of said conveyor in convenient proximity to material adjacent to any part of said coal face while maintaining its delivery end in loading relation above a pit car suitably positioned upon the mine track.
